UNITED STATES PATENT OFFICE.

CHRISTEN WITTRUP, OF CLIFTON, ILLINOIS.

PUZZLE.

1,294,013.

Specification of Letters Patent. Patented Feb. 11, 1919.

Application filed February 15, 1917. Serial No. 148,851.

To all whom it may concern:

Be it known that I, CHRISTEN WITTRUP, a citizen of the United States, residing at Clifton, in the county of Iroquois and State 5 of Illinois, have invented certain new and useful Improvements in Puzzles, of which the following is a specification.

This invention relates to improvements in puzzles designed particularly for the amusement and entertainment of society. A further object is to provide an interesting mechanical device for testing the skill and 10 steadiness of nerve of the party engaged. A further object is to provide a device of this 15 class that is cheap to manufacture and that is simple in its construction. With the foregoing and other objects in view the invention consists in the combination and arrangement of parts to be hereinafter fully 20 described, pointed out in the appended claims and illustrated in the accompanying drawing which forms a part of this specification and in which—

Figure 1 is a view of my device in cross 25 section.

Fig. 2 is a perspective view of the device partly broken away to afford a better illustration.

Like reference characters denote corresponding parts in both views.

The reference numeral 1 denotes an oblong box having a removable glass top 2 and in said box 1 another box 3 is disposed, the 30 said box 3 having less depth than the box 1 so that the top of said inner box is disposed below the glass top 2 of box 1. The box 3, further, is substantially smaller than the box 1 and is spaced away from the sides of 35 that box by the horizontal partitions 4, 5, 6, 40 7. The box 3 is formed with the interior vertical partitions 8, 9 which are spaced from the ends of said box by the horizontal partitions 10, 11 respectively.

The horizontal partition 4 of box 1 is 45 formed with an aperture 12, one end of the box 3 is formed with an aperture 13, the horizontal partition 11 of box 3 is formed with an aperture 14, the vertical partitions of box 3 are formed with apertures 15, 16, 50 17 respectively and the floor 17 of said box 3 is formed with a circular depression 18. The puzzle is to pass a marble or small ball 19 from the floor 20 of box 1 up through

the aperture 12 in horizontal partition 4 and then along that partition to and over 55 the partition 7 and upon the partition 6. From the partition 6 the ball is to be passed through the aperture 13 in one end of box 3, through the aperture 14 in partition 11, through the aperture 16 in partition 9 and 60 lastly into the grooved depression 18 of the floor 17. When this is accomplished the ball may be passed through the aperture 15 of vertical partition 8 and the game started again.

The ball is to be passed through the several apertures and over the several partitions solely by movement of the box 1 held in the operator's hands. A sudden jerk of the box may cause the ball to jump up from the floor 70 20 of box 1 through the partition 12 and similar movements of the box must be made to drive the ball over the complete course, the operator's skill being the determining factor in the successful solution of the 75 puzzle.

What is claimed is:—

1. In a puzzle, an outer box, an inner box having one apertured end, partitions connecting said boxes, one of said partitions being apertured, apertured vertical partitions for said inner box, horizontal partitions connecting said vertical partitions and the walls of said inner box, one of said horizontal partitions being apertured, and a ball having a 85 diameter less than any of said apertures.

2. In a puzzle, an outer box having a removable transparent top, an inner box of less depth than said outer box and having one apertured end and a depression in its 90 floor, horizontal partitions connecting said boxes, one of said partitions being apertured, apertured vertical partitions for said inner box connecting two opposite sides thereof, horizontal partitions connecting said vertical partitions and the walls of said inner box, one of said horizontal partitions being apertured, and a ball having smaller diameter than any of said apertures.

In testimony that I claim the foregoing 100 as my own I have hereto affixed my signature in the presence of two subscribing witnesses.

CHRIS. WITTRUP.
